5 Claims. (Cl. 51—92)

The object of the present invention is a universal precision sharpening machine comprising a work-table moving longitudinally and a sliding grinding-wheel support moving transversely. This sharpening machine is characterized in that the work-table rests on a rigid bed having the shape of a bridge with two pillars and mounted on a common frame, and in that the sliding support rests on a transverse slide provided on this frame between the two pillars and extending backwards from the latter, the forepart of the sliding support engaging itself freely under the middle part of the bed, the whole in such a way as to eliminate any risk of error resulting from elastic deformation of the moving elements or of their support.

The attached drawings represent schematically, by way of example, an embodiment of the sharpening machine making the object of the invention. Fig. 1 is an elevation and Fig. 2 a side view thereof. Fig. 3 is a partial longitudinal section, the left and right half of which correspond respectively to the lines A—A and B—B of Fig. 2. Fig. 4 is a partial transverse section according to line C—C of Fig. 3.

In the embodiment represented, the machine comprises a frame 1 possessing on the one hand a transverse slide 2 and on the other hand a longitudinal bed in the shape of a bridge with two pillars 3, on which moves a work-table 4. The latter is controlled by a hand-wheel 5. The slide 2 carries a slider 7 on which is mounted a grinding-wheel supporting column 8. This slide extends as far as the front of the machine, the forepart of the slider having free passage between the two pillars under the middle part of the bed of the work-table. The slider can be controlled with precision by the hand-wheels 9 and 9' with micrometrical division, and a lever 10 is provided for quick displacements. A handle 11 permits to pass from one to the other of these two means of control.

The lever 10 drives a shaft 12, shown on Fig. 3, which carries a fixed toothed wheel 13 driving in its turn a pinion that is itself fixed on a toothed wheel 14; the latter can rotate freely on a pivot mounted in the frame and engages into a rack 15 fixed on the slider. The handle 11 extends into the frame through an axis 16, the other end of which carries a small eccentric. The latter fits in an eyelet 17 of a bolt, whose square head can slip along a groove provided in an oblong nut 18, which itself can slide along a V provided in the transverse slide.

The control hand-wheels 9 and 9' are mounted

each at one end of a micrometrical screw 19 co-operating with the nut 18.

The grinding-wheel supporting column 8 (Fig. 4) can rotate in a sleeve 20, which itself can move vertically in a muff 21 fixed on the slider. To that effect, the sleeve carries at its lower end an arm 22 provided with a nut 23 in which engages a micrometrical screw 24 driven by a pinion 25 mounted on a thrust ball-bearing.

10 A hand-wheel 26 with micrometrical graduation is mounted rotatably on the slider by means of an axis, the other end of which carries a toothed wheel 27. The latter engages on the one hand into the pinion 25 and on the other hand into an intermediate pinion 28 driven by a pinion 29. This pinion is mounted at the end of the axis of a knob 30 intended to control the accurate vertical displacements of the grinding-wheel support. The quick displacement of the latter is 20 insured by the handle 31 mounted directly on the hand-wheel 26.

The operation of the machine is as follows:

25 The cutters of other tools to be sharpened are disposed on the work-table by means of accessories not shown. The grinding wheel is brought quickly into approximate working position by operating the lever 10, and then, the accurate position is reached by operating one or the other of the hand-wheels 9 and 9', after having blocked 30 the handle 11. The symmetrical disposition of the organs 30 and 31 controlling the vertical adjustment device of the grinding-wheel has the advantage of making them accessible from both sides of the machine.

35 The chief advantage of this sharpening machine is to possess a work-table that is particularly well supported by a bed of very stiff shape leaving free passage for the sliding grinding-wheel support; this latter is mounted on the same 40 frame as the bed, so that the relative position of the grinding-wheel with respect to the piece to be sharpened can be determined with a high accuracy and that any risk of error due to elastic deformation of the movable elements or of their 45 support is completely eliminated.

It is obvious that the invention is not limited to the embodiment represented. In particular, the shape of the bed and of the work-table can make the object of numerous alternatives remaining within the scope of the invention.

50 What is claimed to be new is:

1. A sharpening machine comprising a frame, a bridge forming a bed and having spaced pillars rigidly mounted on the frame, a work-table mounted on and movable longitudinally of the

bed, a sliding support movable transversely of the frame and having a portion adapted to move through the space beneath the bed and between the pillars, means including a rack for quick displacement of said support, means including a micrometrical screw for fine adjustments of the support, and a grinding wheel column carried by and vertically adjustable relative to said support.

2. A universal precision machine comprising a frame having a transverse slideway extending thereacross, a bed at the front of the frame in the form of a bridge having spaced pillars rigidly mounted on the frame on opposite sides of the slideway, a work table mounted on and movable longitudinally of the bed, a sliding support movable along the slideway transversely of the frame and having the forward portion movable through the space beneath the bridge and between the pillars and having the rear portion extending rearwardly of the bed, a grinding wheel support carried by and vertically adjustable relative to the rear portion of the sliding support, and the parts being arranged to eliminate any risk of error resulting from elastic deformation of the moving elements or their support.

3. A machine as claimed in claim 2, in which means are provided for effecting quick adjustments of the sliding support, including a manually operable rack, and means including a micrometrical screw for effecting fine adjustments of the support.

4. A machine in accordance with claim 2, in which a manually operable rack is provided for effecting quick adjustments of the sliding support, means for effecting accurate displacements of the sliding support, including a nut sliding in the slideway and provided with a groove, a micrometrical screw coacting with the nut and operable from either end of the slideway, and a locking device including a bolt engaging with the groove provided in the nut, substantially as and for the purposes set forth.

5. A machine according to claim 2, in which the means for mounting the grinding wheel support includes a muff fixed on the slideway, a sleeve slidably mounted in the muff, a vertical column forming the support rotatably arranged in the sleeve, and means for effecting quick and accurate displacements of the sleeve.
